UNITED STATES PATENT OFFICE

1,925,912

IMPELLER FOR WATER CRAFT

Ray D. Strout, La Salle, Ill.

Application September 26, 1932
Serial No. 634,954

2 Claims. (Cl. 115—28)

This invention relates to certain novel improvements in impellers for watercraft, and has for its principal object the provision of an improved construction of this character which will be highly efficient in use and economical in manufacture.

This application is similar to my abandoned application filed June 11, 1931, Ser. No. 543,549, on an Impeller for watercraft.

The object of this invention is to provide a simple, relatively inexpensive device for impelling watercraft, especially small boats, in a manner similar to that which is known as "sculling".

Other objects will appear hereinafter.

The invention consists in the novel combination and arrangement of parts to be hereinafter described and claimed.

The invention will be best understood by reference to the accompanying drawing, showing the preferred form of construction and in which:

20 Fig. 1 is a side elevational view of a preferred form of the invention associated with a typical watercraft or boat;

Fig. 2 is a top plan view of the same on line 2—2 of Fig. 1;

25 Fig. 3 is a perspective view of the new device detached from the boat;

Fig. 4 is a sectional view on line 4—4 in Fig. 3;

Fig. 5 is a sectional view on line 5—5 in Fig. 3; and

30 Fig. 6 is a sectional view on line 6—6 in Fig. 4.

In the drawing, which illustrates a preferred form of the invention, the same is indicated generally at 10 and is associated with a typical watercraft or small boat 11 of conventional design.

35 The new impeller comprises a vertical support or standard 12 for attachment to the boat 11, as shown. Pivotedly mounted on this support 12 by means of a sleeve 13, for swinging movement in a substantially horizontal plane, is

40 an operating member 14 which has at one end a vertically extending supporting portion 15. This operating member 14 is mounted between its end on the support 12 so that one end portion 25 of the rod 14 serves as a handle.

45 Pivotedly mounted, as at 17, on a depending portion 15 of the operating member 14, for swinging movement in a substantially horizontal plane, is an impeller blade 16. This pivotal mounting of the blade 16 on the depending arm 15 may be

50 effected in a number of different ways but a preferred way of doing this is shown and consists in forming the blade 16 of a sheet of metal which is bent back upon itself about the depending arm 15, as at 17 (Figs. 4 and 6); the ends of the sheet 16 being joined together as at 18, and the opposed

substantially parallel leaves 19 of the blade 16 being separated by spacers 20.

The lower edge of the portion 17 of the blade 16 bears on a retaining collar 21 attached to the depending supporting arm 15. The blade is prevented from moving upwardly on the arm 15 by means of a collar 22 attached to arm 15. Collar 22 is disposed in a notched portion 24 of the blade 16. This collar 22 has formed integral therewith a pair of divergent arms 23 which act as stops to limit movement of the blade 16, relative to its supporting arm 15, in a manner presently to be described.

In use the rod 10 is pivotally manipulated back and forth in a "sculling" motion, by means of handle 25, causing the blade 16 to move back and forth through the water, as indicated in dotted lines (Fig. 2); the blade thus imparting motion to the craft 11. As the arm 15 is moved back and forth between the extremities of its arc of movement the blade 16 pivots at 17 on the arm 15 and abuts first one and then the other of the stop arms 23, which thus limit movement of the blade 16 relative to its supporting arm 15.

Suitable mechanical means (not shown) may, if desired, be associated with the rod 14 to oscillate the same back and forth if desired.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. An impeller for small watercraft, comprising an operating member, means for pivotally mounting said operating member between its ends on a small watercraft, said operating member including a vertically depending supporting portion, an impeller blade having one end pivotally mounted on said depending portion, said blade being formed from a single continuous sheet of material and including substantially parallel leaves, said leaves being joined together at one end and being bent around and embracing said supporting portion at their other ends, and a member on said supporting portion including a pair of divergent stop arms for limiting pivotal movement of said blade relative to said supporting portion.

2. An impeller for small watercraft, comprising

an operating member, means for pivotally mounting said operating member between its ends on a small watercraft, said operating member including a vertically depending supporting portion, an impeller blade having one end pivotally mounted on said depending portion, said blade being formed from a single continuous sheet of material and including substantially parallel leaves, said leaves being joined together at one end and being bent around and embracing said supporting

portion at their other ends, said blade having a cut-out portion providing a notch therein at the intersection of the upper edge of the blade and the portion thereof that embraces said supporting portion, and a member on said supporting portion projected into said notch and including a pair of divergent stop arms for limiting pivotal movement of said blade relative to said supporting portion.
